(21) Appl. No.: **29/537,266**

The ornamental design for a battery cover for mobile computer, as shown and described.

DESCRIPTION

(22) Filed: **Aug. 24, 2015**

FIG. 1 is a top front right perspective view showing a first embodiment of a battery cover for mobile computer showing my new design;

(51) LOC (10) Cl. 13-02

FIG. 2 is a bottom front left perspective view thereof;

(52) U.S. Cl.

FIG. 3 is a front view thereof;

USPC **D13/119**

FIG. 4 is a left side view thereof;

(58) **Field of Classification Search**

FIG. 5 is a right side view thereof;

USPC D13/103-106, 110, 119-121, 184;

FIG. 6 is a top view thereof;

429/96-100, 163, 176

FIG. 7 is a bottom view thereof; and,

CPC Y02E 10/563; Y02E 10/56; Y02E 10/566;

FIG. 8 is a top front right perspective view thereof, shown in use.

Y02E 10/58; Y02E 10/541; Y02E 70/30;

FIG. 9 is a top front right rear perspective view showing a second embodiment of a battery cover for mobile computer showing my new design;

Y02E 60/76; Y02E 60/126; Y02E 60/124;

FIG. 10 is a bottom front left perspective view thereof;

Y02E 60/122; Y02E 40/72; H01M

FIG. 11 is a front view thereof;

2/0222; H01M 2/1044; H01M 2/30;

FIG. 12 is a left side view thereof;

H01M 2/34; H01M 10/00; H01M

FIG. 13 is a right side view thereof;

10/0525; H01M 10/06; H01M 10/345;

FIG. 14 is a top view thereof;

H01M 10/46; H01M 10/465; H01M 8/00

FIG. 15 is a bottom view thereof; and,

See application file for complete search history.

FIG. 16 is a top front right perspective view thereof, shown in use.
